UNITED STATES PATENT OFFICE.

EDMUND J. KIRAS, OF WOODSDALE, KANSAS.

BROOM-HEAD.

1,071,820.

Specification of Letters Patent. Patented Aug. 26, 1913.

Application filed June 26, 1912. Serial No. 706,007.

To all whom it may concern:

Be it known that I, EDMUND J. KIRAS, a citizen of the United States, residing at Woodsdale, in the county of Stevens and 5 State of Kansas, have invented new and useful Improvements in Broom-Heads, of which the following is a specification.

My invention relates to improvements in broom heads, adapted to be refilled by the 10 consumer at small cost and with facility; the objects in view being to provide a simple means for engaging the broom-corn and a readily operatable device for holding such securing means in operative position.

15 With the above and other objects in view, my invention relates to such details of construction and in the arrangement and combination of parts as will be hereinafter more fully described and specifically pointed out 20 in the appended claims.

In describing my invention in detail reference will be had to the accompanying drawings wherein like characters denote like or corresponding parts throughout the several views, and in which—

Figure 1 is a side elevation of my invention. Fig. 2 is a cross sectional view thereof taken on line 2—2, Fig. 1. Fig. 3 is a front elevation of one of the sections of the body 30 portion of my device. Fig. 4 is a detail sectional view illustrating the joint of the body sections. Fig. 5 is a cross sectional view through the broom handle engaging extensions, and, Fig. 6 is a fragmentary view in 35 section, illustrating one of the broom handle engaging extensions.

Referring to the drawings, hollow sections 1 are provided and collectively form a hollow body, casing or fiber-receiving member. The sections have extensions 2, formed 40 thereon and have their lower edges turned inwardly as at 3, for the purpose herein-after appearing. The outer edges of the sections are bent as shown at 4, whereby 45 they may be securely held in engagement with each other as shown. For the purpose of holding the extensions in engagement with each other, their edges are rolled as at 5. The extensions may be attached to the han-

dle 6, rigidly by means of the transversely 50 extending pins 7.

Gripping plates or jaw members 8, of spring metal, are provided and normally tend to move toward each other or inwardly, so as to firmly grip the broom straw or 55 fiber. Said gripping members 8 are riveted to the sections 1 as shown, or secured in any other suitable way thereto. In connection with the substitution or withdrawal of broom straw from between the gripping 60 members 8, suitable means is provided whereby the members 8 may be drawn away from each other and maintained in such position preparatory to the insertion of substitute straw. Said means as shown, consists of screw threaded bolts or pins 12 connected to the gripping members 8 and extending through enlarged slots or openings 13 in the sections 1. Beyond the sections 1 the screw threads of the pins 12 are engaged 70 by a winged nut 14. It will be realized that when it is desired to move the members 8 away from each other, that the nuts 14 are turned in the proper direction so that the engagement thereof with the threads, will 75 move the same apart. Upon unscrewing the nuts 14, it is obvious that the members 8 will be free to spring toward each other so as to effectively grip the substituted straw.

The greatest of stress is laid upon the 80 simplicity of my invention and it is thought that the advantages and novel features of the same will be readily appreciated from the foregoing disclosure.

I desire it to be understood that I may 85 make slight changes in the arrangement and combination of parts without departing from the spirit of my invention, provided however such changes fall within the scope of the subjoined claims.

Having thus fully described my invention, what I claim as new, and desire to secure by Letters Patent, is:—

1. A broom head including a fiber receiving casing, a retractable gripping jaw within the casing, a projecting member on said jaw extending through the casing and an adjustable member outside the casing 95

adapted to disengage the jaw from the broom fiber.

2. A broom head including a fiber receiving casing and a pair of gripping jaws within said casing made of yieldable material, said casing provided with an opening adjacent each gripping member, a bolt ex-

tending through each opening and connected to the adjacent jaw and a nut on said bolt exterior of the casing.

EDMUND J. KIRAS.
